UNITED STATES PATENT OFFICE

JOSEPH GARDNER AND JOSEPH HUGH STOTT GARDNER, OF PATRICROFT, NEAR MANCHESTER, ENGLAND, ASSIGNEES TO L. GARDNER & SONS LIMITED, OF PATRICROFT, NEAR MANCHESTER, ENGLAND, A BRITISH COMPANY

INLET VALVE OF INTERNAL COMBUSTION ENGINES

Application filed May 10, 1930, Serial No. 451,468, and in Great Britain October 12, 1929.

This invention relates to the inlet valves of internal combustion engines, and has for its object to provide improved means for increasing the turbulence within the engine cylinder or cylinders during and after admission through the said valves.

It is known to provide a projecting wall which extends partly around the edge of one side of an inlet valve, such wall being within the valveway so that it obstructs the flow through the valveway at its side of the valve and increases turbulence in the engine cylinder.

In accordance with our invention, the means which obstruct the throughway at one side of an inlet valve consist of a raised platform-like part which extends inwards from the valve edge to the valve stem so as to provide a directing path across the valve back to the part of the valve edge where the air or charge can issue into the engine. The inlet branch leading to the valve is so disposed as to direct the charge over the said platform to the other side of the valve, and the clearance space around the valve and in the cylinder bore is made to increase from adjacent to the part of the valve where the said platform is situated so that increased clearance is provided where the air or charge issues through the valve.

Referring to the accompanying sheet of explanatory drawings:—

Figure 1 is a sectional elevation through an engine cylinder block on the line A B C of Figure 2 and through the cylinder head on the A B D of Figure 2, the valve being shown in elevation.

Figure 2 is a plan view of the cylinder block with the valve shown in position and the direction of the inlet branch leading to said valve being indicated.

Figure 3 is a sectional view of the valve on the line D B E of Figure 2.

The same reference letters in the three views indicate the same parts.

The inlet valve *a* has a baffle *b* arranged upon the back thereof which extends round a portion of the valve and inwards towards the valve stem *c* so as to provide a raised portion at one side of the back of the valve.

Such baffle or raised portion may be hollowed out at *d* by machining to reduce the weight of the valve as shown in Figures 1 and 3. The axial depth of the baffle *b* is greater than the stroke of the valve so that no throughway is ever available at the side of the valve where the baffle is situated. The inlet branch *e* which leads to the inlet valve *a* is so directed relatively to the valve opening into the engine cylinder as shown in Figure 2 as to cause a swirling motion of the air or charge around the cylinder in the direction of the arrow *f* and the baffled part of the valve is arranged so that it ensures that the air or charge can only pass in a forward direction into the cylinder to produce the swirling motion and can not pass therein in such a way as to oppose or retard the swirling air or charge.

To provide a large area around the valve *a* for the passage of air or the charge into the cylinder *g* in the desired direction, we make the clearance space *h* in the cylinder bore around the valve of eccentric formation as shown in Figure 2, the space gradually increasing from adjacent to the part of the valve where the baffle *b* is situated and being completed at *i* in a direction tangential to the cylinder bore. Such shaping of the clearance space also assists in the production of turbulence during the period of admission, the turbulence continuing during compression.

We find that the provision of a raised platform like part *b* at the back of one side of the valve serves in an effective manner to direct the incoming air or charge to the unshielded or unbaffled side of the valve, whilst the disposition of the inlet branch or conduit and the shape of the clearance space as before described, ensure that the portion of the valve at which the passage of air or the charge takes place is very efficient so that a very large valve is not necessary.

The baffle *b*, may, if desired, be attached to the rear of the valve instead of being made integrally therewith.

Claims:—

1. An inlet valve of an internal combustion engine having a raised platform like part at one side of the back of the valve in order to

provide a permanent closure for that side of the valve throughway and to direct the incoming air or charge to the unshielded or unbaffled side of the valve.

- 5 2. The combination with an inlet valve as claimed in claim 1, of a clearance space around the valve in the engine cylinder bore which increases from adjacent to the shielded side of the valve.
- 10 3. Air or charge inlet arrangements of internal combustion engines comprising an inlet valve having a hollow raised platform-like part formed integrally therewith at one side of the back of the valve, an inlet branch directing the incoming air or charge to the other side of the back of the valve, and a clearance space in the engine cylinder bore of excentric shape relatively to the valve, such space increasing from adjacent to the platform side of the valve and terminating with its wall tangential to the cylinder wall.
- 15 4. Air or charge inlet arrangements of internal combustion engines, comprising an inlet valve having shielding means thereon for obstructing the flow through the valveway at one side of the valve when the latter is opened, and a clearance space in the engine cylinder bore around a portion of the valve periphery, such space increasing from adjacent to the shielded side of the valve.
- 20 5. Air or charge inlet arrangements of internal combustion engines comprising the combination with a cylinder of the engine of an inlet valve disposed partly in the cylinder bore and partly in a pocket or clearance space in the cylinder wall, a projecting shield at one side of the back of the valve obstructing the flow through the valveway at one side of the valve when the latter is opened, the said pocket being of excentric form with relation to the valve and providing a gradually increasing space from adjacent to the said shield.
- 25 6. Air or charge inlet arrangements of internal combustion engines comprising the combination with a cylinder of the engine of an inlet valve disposed partly in the cylinder bore and partly in a pocket or clearance space in the cylinder wall, a projecting shield at one side of the back of the valve, the said pocket being of excentric form with relation to the valve and providing a gradually increasing space from adjacent to the shield, the pocket terminating with its wall tangential to the engine cylinder wall.

In testimony whereof we have signed our names to this specification.

JOSEPH GARDNER.
